UNITED STATES PATENT OFFICE.

THOMAS BURNS, OF EDINBURGH, SCOTLAND.

APPARATUS FOR SCOURING AND WASHING SKINS, &c.

SPECIFICATION forming part of Letters Patent No. 478,499, dated July 5, 1892.

Application filed September 13, 1889. Serial No. 323,886. (No model.) Patented in England February 9, 1889, No. 2,311, and July 10, 1889, No. 11,133; in Victoria August 20, 1889, No. 7,013; in South Australia August 20, 1889, No. 1,397; in New South Wales August 21, 1889, No. 1,639; in Queensland August 22, 1889, No. 826; in New Zealand August 29, 1889, No. 3,918, and in Canada October 27, 1891, No. 37,692.

To all whom it may concern:

Be it known that I, THOMAS BURNS, skin-
ner, tanner, and wool merchant, a subject of
the Queen of Great Britain and Ireland, of
5 Messrs. White, Burns & Co., Bonnington Skin
Works, and 1 Pilrig Street, Edinburgh, in
the county of Mid-Lothian, Scotland, have in-
vented Machinery or Apparatus for Scour-
ing and Washing Skins and Wool and Analo-
10 gous Materials, (for which I have obtained
Letters Patent in the United Kingdom of
Great Britain, dated February 9, 1889, No.
2,311, and dated July 10, 1889, No. 11,133, re-
spectively; in New Zealand, dated August 29,
15 1889, No. 3,918; in New South Wales, dated
August 21, 1889, No. 1,639; in Queensland,
dated August 22, 1889, No. 826; in Victoria,
dated August 20, 1889, No. 7,013; in Australia,
dated August 20, 1889, No. 1,397, and in
20 Canada, dated October 27, 1891, No. 37,692;)
and I do hereby declare that the following is a
full, clear, and exact description of the inven-
tion, which will enable others skilled in the
art to which it appertains to make and use
25 the same.

This invention relates to machinery or ap-
paratus for scouring and washing skins and
wool and analogous materials, and has for its
objects to facilitate the said scouring and
30 washing operations, these operations being
done in a much more efficient manner, with
practically no loss of wool, in less time, and
at less expense than is obtainable at present
by the hand process.

35 In carrying out my said invention I em-
ploy a large oblong trough, through which I
cause a continual flow of water to pass, and
having a suitable number of pairs of squeezers
40 mounted at intervals along its length, the said
squeezers being preferably a pair of rollers
capable of adjustment, so as to regulate the
pressure on the material being washed or
scoured. This trough also carries the neces-
45 sary entering, adjusting, and guiding rollers,
as also the leading band or rollers and guiding-
ropes for the leading through of the ma-
terial; and, further, I employ another oblong
trough, through which a continual flow of wa-
50 ter passes, for steeping the skins in, this
trough having mounted at its one end a num-

ber of rollers (some of which are formed
with spurs or grooves along their length) for
feeding the material out of the steeping-trough
onto the leading band or rollers of the first-
mentioned trough. The said rollers and 55
squeezers which require to be driven are
driven by means of spur-gearing, endless
band, chain, and chain-wheels or their equiva-
lents from one or more main driving-shafts,
these driving-shafts being driven by steam, 60
hand, or horse power.

In cases where skins which have been
treated with lime or other substances on their
flesh sides are to be washed or scoured I may
mount a spurred or grooved roller across the 65
steeping-trough immediately in front of the
entering set of rollers, and which I drive in
the opposite direction to that of the other roll-
ers, so that the spurs or top edges of grooves
scrape the flesh side of the skin as it passes 70
over it. The said troughs and their connec-
tions may be built upon suitable foundations
and used as fixtures, or they may be mounted
on wheels in any suitable manner and there-
fore made portable and capable of being 75
moved from place to place. The said troughs
may also be used jointly with one another or
separately, as desired.

In order that my said invention may be
more readily carried into effect and more 80
easily understood, I will now proceed to de-
scribe it with reference to the annexed draw-
ings.

In the drawings, Figures 1 and 2, Sheet 1,
are elevation and plan of that part of my said 85
invention which I term the "washing" and
"scouring" machinery as used for skins.
Figs. 3 and 4, Sheet 2, are elevation and plan
of that part of my said invention which I
term my "steeping-trough" and "entering set 90
of rollers," as used for skins and shown in con-
junction with the entering end of my washing
and scouring machinery.

A, Figs. 1 and 2, Sheet 1, is a large oblong 95
trough or box, made of wood, iron, or other
material, for holding water, which is caused to
flow continuously in and out by any suitable
means. The said trough may be mounted in
any suitable manner to foundations *a* as a
fixture, or it may be mounted on wheels, so 100

as to be portable and therefore capable of being moved from one place to another. This trough carries a number of pairs of squeezers B, B', and B'', entering-roller C, discharge-
5 roller D, guide-rollers E, E', E'', E''', and E''', endless band F, guide-ropes G, driving-shaft H, and gearing K, the said rollers, driving-
shaft, and gearing being all carried in suitable bearings either formed on the said trough
10 or attached thereto by any suitable means. For allowing of the said trough being cleaned out, when desired, I may provide one or more openings J in or near its bottom, the said openings being capable of closing by any suitable means.

As shown in the drawings, I preferably employ six pairs of squeezers B, B', and B'', (though I may use any other number of pairs of squeezers,) some of them working under, 15 some in, and some above the water and mounted across the trough at intervals along its length, the said squeezers being preferably a pair of wooden or iron rollers packed or covered with yarn, rope, or india-rubber b, so as to form a yielding surface, and so mounted that the desired degree of pressure may be applied on the material passing through them, the said pressure being obtained by mounting the one roller b² in fixed or stationary 20 bearings b³, while the other roller b⁴ is carried in sliding or movable bearings b⁵, which are also provided with spiral or other springs b⁶ and the necessary screw arrangement for adjusting the pressure on the springs, the said 25 squeezers being driven in any suitable manner from the main driving-shaft by means of spur-wheel gearing, endless band, chain and chain-wheels, or their mechanical equivalents, but preferably by keying a spur-wheel k, Fig. 30 2, onto the driving-shaft H, which carries the bottom roller of the first set of squeezers B. The said spur-wheel transmits its power into an intermediate wheel k', thence into an intermediate k² on top roller of squeezers B', 35 thence into an intermediate k³, thence into a driver k⁴, keyed on the bottom roller of the squeezers B'', thence into a central intermediate k⁵, from which it repeats the same routine, only backward, till it expends itself 40 at end squeezers B, the top rollers on the pairs of squeezers B and B'' being driven from the under ones by means of spur-wheels L, the said driving-shaft H being driven by steam, hand, or horse power.

For the purpose of carrying or leading the material to be washed through the said squeezers I employ an endless band F, of wire-cloth, cloth, or belting, which is caused to pass over the under rollers of the squeezers 45 B, B', and B'' and partly round the entering-roller C, the discharge-roller D, and guide-rollers E and E', the said endless band being tightened or slackened by means of mounting the entering-roller C or the discharge-
50 roller D, or both, as shown, in sliding or movable bearings c d, which are carried in suitably grooved or recessed brackets c' d', which

are either formed on the said trough or attached thereto by suitable means and provided with the necessary screw arrangements 70 c² d², the said band being also adjustable transversely by means of mounting the one end of the guide-roller E' in a movable bearing e, carried in a suitable bracket e' and provided with the necessary screw adjusting arrangement e², the opposite end of said guide-roller working in an oval journal to allow of its movement.

In order to guide the material in passing through the squeezers and so prevent it from 80 getting out of place or winding round any of the top rollers, I employ three, five, or any number of endless ropes G, which I cause to pass under the top rollers of the squeezers and over the grooved guide-rollers E³ and E⁴, 85 the said ropes working in grooves formed in the said top rollers of the squeezers, the said grooves being such that the rope fills up the space of groove, so that an equal surface is always pressing on the material, the said 90 ropes being capable of adjustment—that is, tightened or slackened—by means of the guide-roller E⁴ being carried in movable bearings e⁴, which work in suitable grooved or recessed brackets e⁵, formed on or fixed to the 95 said trough, and provided with the necessary screw adjusting arrangement e⁶. All the rollers hereinbefore mentioned may be made of wood or iron, or both, or any other suitable material. The flow of water into 100 the said trough is preferably such that the clean water on entering the machine falls on top of the small guide-roller E², (which is here mounted to prevent the weight of the falling water from bagging the endless band F,) and 105 thus comes into contact with the material immediately before it passes out of the machine, or when the material is nearly cleaned. The water then passes out of the machine by overflowing in its dirtiest state at the entering end A', where it comes in contact with the material in its dirty state as it enters the machine, though I may use any other arrangement of water supply and outlet. As a 110 modification of my said endless band for carrying or leading the material through the squeezers I may employ in lieu thereof a number of sets of small wooden or iron rollers, each set being so mounted as to occupy the space between each pair of the squeezers, 115 and I also mount another set of these rollers at the entering end of the machine for the purpose of leading the material to the first pair of squeezers, these rollers being all driven by spur-gearing, endless band, or chain 120 and chain-wheels from the main driving-shaft, this modification doing away with the endless band, guide, and adjusting-rollers for same, as hereinbefore described.

N, Figs. 3 and 4, Sheet 2, is the steeping-trough, preferably oblong in shape and made of wood, iron, or other material, through which a continual flow of water is caused to pass, the said flow preferably entering at the

end where the rollers are mounted and passing out at the other. This trough carries a number (preferably eight) of entering-rollers M at its one end. The said rollers may be 5 made of wood, iron, or other suitable material and mounted in suitable bearings either formed on the trough or on suitable brackets R, which are fixed to the trough by bolts or their equivalents, and preferably driven from 10 the main driving-shaft H of the washing or scouring machinery by means of spur-gearing P, endless band, chain and chain-wheels, or their equivalents, though I may, if desired, provide a separate driving-shaft for them on 15 the said trough. These rollers M are preferably arranged as shown, m being a spur or grooved roller of, say, about twelve inches in diameter, m' and m² being two smaller spur or grooved rollers, and the remainder plain 20 rollers, so that on the material or skin being lifted from the trough and placed on top of the spur-roller m the spurs tend to pull the material or skin up onto the other rollers, which then lead it on till it falls on the end- 25 less leading-band F of the washing or scouring machinery. This band then enters them into the said machinery.

Where lime or other substances are used for preserving or cleaning the flesh sides of 30 the skins, I mount another spur or grooved roller S in suitable bearings s, these being so formed as to allow of the roller's removal when not required. This roller is driven in the opposite direction to that of the others by 35 means of spur-gearing P' or its equivalent, so that as the skins are being drawn up from the trough by the rollers M the spurs on the roller S rub or scrape the lime off the flesh side of the skins before they enter the machinery.

40 The said trough N may be mounted on suitable foundations as a fixture or it may be mounted on wheels, so as to be portable and capable of being moved from place to place, and for the purpose of cleaning it out or run-

ning off the water I may provide one or more 45 suitable openings T in or near its bottom, the said openings being provided with suitable doors or covers.

If desired, I may use my first-mentioned trough and mountings as machinery or apparatus for scouring and washing and dispense with the steeping-trough and its mountings, though when skins are being washed or scoured I prefer to use both troughs jointly. 50

I claim—

1. In machinery or apparatus for scouring and washing skins, wool, &c., the combination of the tank A, carrying a series of squeezing-rolls and grooved guide-rollers E, E', and E², an endless band F, passing about said guide-rollers and between the squeezing-rolls, adjustable pulleys C and D for regulating the tension of the endless band, endless ropes G, passing around grooved guide-rollers E³ E⁴ and between the squeezing-rolls, and gearing 65 for connecting together and simultaneously driving the squeezing-rolls, substantially as described.

2. In a machine or apparatus for scouring and washing skins, wool, &c., the combination 70 of a tank of ordinary or suitable construction carrying a series of squeezing-rolls, a steeping-trough N, carrying a series of entering-rollers mounted upon the end of said trough, a spur-gear P, and means for connecting together and driving the gearing of the tank and trough simultaneously, substantially as 75 hereinbefore set forth.

In testimony whereof I have signed my name to this specification in the presence of 80 two subscribing witnesses.

THOMAS BURNS.
